ELECTRIC FAN

George Zint, Wapakoneta, Ohio

Application January 28, 1938, Serial No. 187,489

12 Claims. (Cl. 230—256)

The principal object of the present invention is to provide, a new and improved electric fan of the oscillating type, including novel provision whereby the extent of oscillation of the fan may be varied as desired.

Another object is to provide for swinging the fan-carrying and driving motor to any of various positions to direct the blasts of air in the most desirable directions, the provision for thus adjusting the fan being of such nature that the adjustment may be quickly and easily performed without hazard, while the fan is in operation.

A still further object is to provide a construction of comparatively simple and inexpensive nature, yet one which will be efficient and desirable.

With the foregoing in view, the invention resides in the novel subject matter hereinafter described and claimed, description being accomplished by reference to the accompanying drawings.

Figure 1 is a side elevation partly in section.

Figure 2 is a rear elevation partly in section.

Figure 3 is an elevation of the side opposite that shown in Fig. 1, partly in section.

Figure 4 is a horizontal sectional view on line 4—4 of Fig. 2.

Figure 5 is a fragmentary disassembled perspective view.

Figure 6 is a detail vertical section on line 6—6 of Fig. 2.

In the drawings above briefly described, a construction has been illustrated for readily attaining the desired ends, and while this construction may be considered as preferred, it is to be understood that numerous variations may be made within the scope of the invention as claimed.

A hollow base 10 is provided, rigidly connected by screw threads or otherwise, with a central tubular standard 11, and a large worm wheel 12 is secured to the upper end of this standard.

Preferably, the standard 11 is provided with an upward extension 13 passing through the worm wheel 12, the upper end of said extension being provided with a head 13' which clamps said worm wheel solidly to the standard 11. Suitably supported within the standard 11 is a thrust bearing 14 upon which a tubular trunnion 15 rests, the upper end of said trunnion being provided with an integral head or cap 16 which overlies and encloses the head 13'. Integral with this head or cap 16 is a plate-like portion 17 of a carrier 18, which carrier is preferably a one-piece casting embodying two vertical side members 19 and 20, a cowl-like casing portion 21 integrally connected with said side members and

with the plate portion 17, two upstanding lugs or arms 22 and 23 between said side members 19 and 20, and a cylindrical stub 24 projecting laterally outward from the upper end of the side member 19.

A bracket 25 carrying the driving motor 26 for the fan 27, is formed with an opening 28 into which the stub 24 projects to pivotally mount said bracket and thus allow upward or downward arcuate adjustment of the motor and fan to direct the air blast in any desired direction with regard to the horizontal. The bracket 25 is formed with another opening 29 at right angles to the axis of the opening 28. In the inner end of this opening 29, there is a friction shoe 30 contacting with the periphery of the stub 24. A coiled compression spring 31 abuts the outer end of the shoe 30, and a clamping screw 32 is threaded in the outer end of said opening 29 in abutting relation with the outer end of said spring. The screw 32 is provided with a hand grip 33 which is preferably of sufficient weight to at least partially counterbalance the weight of the motor 26. When the screw 32 is sufficiently tightened, spring 31 forces shoe 30 against the stub 24 with such force as to frictionally clamp the bracket 25 to said stub, holding said bracket in any position to which it may have been adjusted. The hand grip 33 serves not only as means for quickly and easily loosening the screw 32, but it further acts as a handle for vertically swinging the bracket 25 upon the stub 24. It is thus an easy matter to so adjust the fan as to direct the air upwardly, downwardly or horizontally. By grasping the hand grip 33 in one hand, turning said hand grip slightly to release the screw 32, swinging said hand grip upwardly or downwardly, and then turning it to tighten the screw 32, the desired adjustment may be conveniently made.

A shaft 35 passes through bearing openings 36 in the side members 19 and 20 of the carrier 18 and is provided at one end with a worm 37 meshing with the worm gear 12. Above this shaft 35 is another shaft 38 rotatably mounted in bearing openings 39 in the side members 19 and 20. Above the shaft 38 is a third shaft 40 mounted in bearing openings 41 in the side members 19 and 20, these openings 41 being coaxial with the cylindrical pivot stub 24. Pinned or otherwise secured to the shaft 40, is a worm wheel 42 meshing with a worm 43 on the motor shaft 44. Secured to the opposite end of the shaft 40 is a gear 45 meshing with an idler 46 which in turn meshes with another gear 47 on one end of the

shaft 38, said gear 47 being meshed with a gear 48 which is loose on one end of the shaft 35. Also loosely mounted on this shaft is another gear 49 meshing with an idler 50, which idler 5 meshes with a gear 51 on the shaft 38. A clutch sleeve 52 is slidably splined or otherwise mounted on the shaft 35 between the two gears 48 and 49, said clutch member serving to selectively connect one or the other of these gears with said shaft. 10 When gear 48 is connected with the shaft 35, the worm 37 will be driven in one direction and consequently the carrier 18 will move arcuately in one direction with respect to the base and the worm wheel 12. When the clutch sleeve 52 connects the other gear 49 with the shaft 35, however, the worm 37 will be driven in the opposite direction, causing reverse movement of said carrier 18.

A reversing fork 53 is operatively connected 20 with the sleeve 52 and is secured upon a shaft 54 rotatably mounted in bearings 55 in the lugs or arms 22 and 23, the outer end of said shaft 54 being provided with a downwardly projecting reversing arm 56 which is operable between two 25 trips 57. When the arm 56 strikes one of these trips 57, the movement of said arm operates the fork 53 to slide the clutch sleeve 52 in one direction, operatively connecting gear 48 with shaft 35. When arm 56 strikes the other of the trips 30 57, the movement of said arm causes the fork 53 to shift the clutch sleeve 52 in the opposite direction, operatively connecting gear 49 with shaft 35. Thus, the driving of the worm 37 first in one direction and then in the other to slowly 35 oscillate the carrier 17 and the parts carried thereby, is attained. The two trips 57 are preferably relatively adjustable. In the present showing, each of said trips is provided with a split ring 58 at its inner end, the two rings of the 40 two trips being frictionally received in shallow grooves 59 in the standard 11. The trips 57 may thus be swung to any desired spaced relation and the friction between the groove bottoms and the rings 58, will hold said trips after adjustment. Preferably, the standard 11 carries a fixed pin 60 which prevents such setting of the trip arms 57 as to allow complete rotation of the carrier 17 with danger of injuring the current conducting wires 61 which lead to the motor 26. 45 These wires pass from a switch 62 within the base 10, upwardly through the tubular standard 11, through the tubular trunnion 15, and through an opening 63 in the head or cap 16, and from this opening extend on to the motor 26.

50 It is preferable that the clutch sleeve 52 have a snap-action in both directions. To insure this, I preferably provide an upstanding arm 64 on one end of the shaft 54 and provide a spring arm 65 of V-shape to coat with said arm 64 to snap it in one direction or the other as soon as said arm is pushed slightly past the crest of the V. In the present disclosure, the arm 65 is provided with a coil 66 surrounding a pin 67 on the carrier 18, the end of said spring opposite the arm 65 being extended at 68 and secured to the carrier 65 by a screw 69.

From the foregoing taken in connection with the accompanying drawings, it will be seen that novel and advantageous provision has been made for carrying out the objects of the invention, and while preferred features have been shown, attention is again invited to the possibility of making variations within the scope of the invention as claimed. Obviously, the invention is not restricted to a motor of any particular type, to fan

blades of one kind or another, nor to materials, proportions, etc. Moreover, it will be obvious that any desired encasing means may be employed for any of the moving parts. In the present showing, most of the gearing is protected by a cover 5 70 extending between and over the side members 19 and 20 of the carrier 18, said cover being secured at 71 to the cowl portion 21 and at 72 to the lug or arm 22. An arched cover plate 73 is also shown for the worm wheel 42 and worm 43, 10 secured by screws 74 to the bracket 25.

I claim:

1. An oscillating electric fan comprising a base, a standard rising rigidly therefrom, a worm wheel secured to the end of said standard most remote 15 from the base, an oscillatory carrier mounted directly adjacent said worm wheel, a fan-driving motor mounted on said carrier, a worm mounted on said carrier and meshing with said worm wheel, reversible gearing mounted on said carrier 20 and operatively connected with said motor and said worm for driving the latter in either direction, a reversing arm for said reversible gearing mounted on said carrier, and fixed trips between which said arm is operable to cause reversing of said reversible gearing when said carrier has turned a predetermined distance in either direction.

2. An electric fan comprising a carrier mounted for rotation, a bracket pivotally mounted on 30 said carrier on an axis transverse to the axis of rotation thereof, means for holding said bracket after adjustment upon its pivot, a fan-driving motor mounted on said bracket, and means for rotating said carrier, including one gear mounted coaxially with the pivot of said bracket, and a second gear meshing with said one gear and secured to the motor shaft, the two gears remaining in mesh during adjustment of said bracket upon its pivot.

3. An electric fan comprising a base having a fixed worm wheel, a carrier rotatably mounted on said base coaxially with said worm wheel, a gear train mounted on said carrier and having a worm wheel at one end and a worm at its other end, the axis of said worm wheel of said train being transverse to the axis of rotation of said carrier, said worm of said train being in mesh with said fixed worm wheel, a bracket pivotally mounted on said carrier coaxially with said axis of said worm wheel of said train for arcuate adjustment, means for holding said bracket in adjusted position, a fan-driving motor mounted on said bracket, and a worm on the motor shaft meshing with said worm wheel of said train, this worm and worm wheel remaining in mesh during adjustment of said bracket upon its pivot.

4. An electric fan comprising a support, a bracket pivotally mounted on said support for arcuate adjustment, a fan-driving motor mounted on said bracket, and means for securing said bracket in adjusted position, said securing means having a hand grip rotatable slightly to release said holding means and then operable as a handle for adjusting said bracket upon its pivot.

5. An electric fan comprising a support, a bracket pivotally mounted on said support for manual arcuate adjustment, a fan-driving motor mounted on said bracket, the relation of said motor with the pivot of said bracket being such that said motor and bracket have a tendency to swing in one direction by gravity, and manually operable means for holding said bracket after manual adjustment thereof, said manually operable means having a heavy operating handle posi-

tioned to at least partially counter-balance the tendency of the motor and bracket to swing in said one direction.

6. An electric fan comprising a support having a laterally projecting cylindrical stub, a motor-carrying bracket having an opening in which said cylindrical stub is received to pivotally mount said bracket for arcuate adjustment, said bracket having a second opening at right angles to and communicating with the first named opening, and means for frictionally clamping said bracket to said cylindrical stub to hold said bracket in adjusted position, said clamping means having a clamping screw threaded in said second opening, and a hand grip on the outer end of said screw, said hand grip being operable both as means for turning said screw and as a handle for vertically adjusting said bracket when said screw is loosened.
20. 7. An electric fan comprising a support having a laterally projecting cylindrical stub, a motor-carrying bracket having an opening in which said cylindrical stub is received to pivotally mount said bracket for arcuate adjustment, said bracket having a second opening at right angles to and communicating with the first named opening, a friction shoe in said second opening in contact with said cylindrical stub, a coiled compression spring in said second opening abutting the outer end of said friction shoe, a clamping screw threaded in said second opening and abutting the outer end of said spring, and a hand grip on the outer end of said screw, said hand grip being operable both as means for turning said screw and as a handle for pivotally adjusting said bracket when said screw is loosened.
8. An oscillatory electric fan comprising a base provided with a fixed worm wheel, a carrier supported by said base to turn upon the axis of said worm wheel, a fan-driving motor mounted on said carrier, a worm mounted on said carrier and meshing with said worm wheel, reversible gearing mounted on said carrier and establishing an operating connection between said motor and said worm for driving the latter in either direction, a reversing member mounted on said carrier for reversing said gearing when moved in either direction, two fixed trips between which said reversing member is operable to effect the required movements of said reversing member to reverse said gearing, and means so constructed and arranged that said trips may be held in relatively adjusted position.
9. An oscillatory electric fan comprising a base provided with a fixed worm wheel, a carrier supported by said base to turn upon the axis of said

worm wheel, a fan-driving motor mounted on said carrier, a worm mounted on said carrier and meshing with said worm wheel, reversible gearing mounted on said carrier and establishing an operating connection between said motor and said worm for driving the latter in either direction, a reversing member mounted on said carrier for reversing said gearing when moved in either direction, and two fixed trips between which said reversing member is operable to effect the required movements of said reversing member to reverse said gearing.

10. An oscillatory electric fan comprising a base, a standard rising rigidly therefrom, a worm wheel secured to said standard, an oscillatory carrier pivotally connected with said standard to turn about the axis of said worm wheel, a fan-driving motor mounted on said carrier, a worm mounted on said carrier and meshing with said worm wheel, reversible gearing mounted on said carrier and operatively connected with said motor and said worm for driving the latter in either direction, a reversing arm for said reversible gearing mounted on said carrier, and fixed trips between which said arm is operable to cause reversing of said reversible gearing when said carrier has turned a predetermined distance in either direction.

11. An electric fan comprising a support having a laterally projecting cylindrical stub, a motor-carrying bracket having an opening in which said cylindrical stub is received to pivotally mount said bracket for arcuate adjustment, said bracket having a second opening at right angles to and communicating with the first named opening, and means for frictionally clamping said bracket to said cylindrical stub to hold said bracket in adjusted position, said clamping means having a clamping screw threaded in said second opening, and a handle on the outer end of said screw.

12. An electric fan comprising a support having a laterally projecting cylindrical stub, a motor-carrying bracket having an opening in which said cylindrical stub is received to pivotally mount said bracket for arcuate adjustment, said bracket having a second opening at right angles to and communicating with the first named opening, a friction shoe in said second opening in contact with said cylindrical stub, a coiled compression spring in said second opening abutting the outer end of said friction shoe, a clamping screw threaded in said second opening and abutting the outer end of said spring, and a handle on the outer end of said screw.

GEORGE ZINT. 55
